CARL G. SCHMID AND ALVIN C. RASMUSSEN, OF INDIANAPOLIS, INDIANA, ASSIGNEES
TO INSLY MANUFACTURING COMPANY, OF INDIANAPOLIS, INDIANA, A COR-
PORATION OF INDIANA.

BUILDING-MATERIAL-HANDLING APPARATUS.

Application filed February 2, 1925. Serial No. 6,266.

This invention relates to improvements in apparatus for handling building material and particularly for elevating and distributing material used in the construction of buildings, especially those constructed of reinforced concrete. It has particular reference to that type of apparatus wherein there is provided a mast or tower adapted to support a chute or chutes for delivering 10 concrete or like material by gravity to the point desired and which mast or tower is provided with an elevating bucket for raising the material to the desired height for delivery to the chute. In the construction 15 work in which this type of apparatus is used there is also the necessity for elevating various kinds of building material which could not be handled by the concrete hoisting bucket and my present invention includes means whereby a material hoisting 20 platform may also be supported and operated upon the mast without in any way interfering with the hoisting and delivering of the concrete and at the same time so 25 balance the various apparatus on the mast that the mast itself will be relieved of twisting and unbalancing strains.

For the purpose of disclosing the invention, one embodiment thereof is illustrated 30 in the accompanying drawings in which

Fig. 1 is a side elevation of an apparatus embodying my invention;

Fig. 2 is a front elevation thereof;

Fig. 3 is a detail cross section on the 35 line 3—3 of Fig. 1;

Fig. 4 is a detail cross section on the line 4—4 of Fig. 1;

Fig. 5 is an enlarged detail of the side elevation showing more particularly the 40 construction of the delivery apparatus;

Fig. 6 is a similar enlarged detail front elevation, and

Fig. 7 is a detail view of the tripping mechanism.

In the construction illustrated the mast or tower 1 comprises four corner posts which are preferably formed of angle iron and are secured in position by diagonal braces which connect the posts together. 45 There are also provided on the interior of the mast suitable gusset plates 2 for bracing and tying the four corner posts together. These plates however are so arranged as to

leave a clear cable passageway through the interior of the mast for a purpose more 55 fully hereinafter described. At a suitable elevation on the mast, depending upon the height of the point at which it is desired to deliver concrete, which elevation in practice is generally about two stories higher 60 than the working point on the building to which it is desired to deliver material, there is provided a head frame 3 which is disposed on one side of the mast and supports at its lower end a chute hopper 4 in such 65 a position that the hopper is at one side of the mast but in a position to receive the material from the hopper bottom hoisting bucket 5. This bucket is provided with a side delivery mouth 6 closed by a pivoted 70 gate 7 and is adapted to deliver its contents into the chute hopper 4, a bridge pan 8 being provided for bridging the space between the delivery end of the bucket and hopper. This bridge pan is supported on 75 suitable links 9 pivotally connected to the bridge pan and pivotally connected to the hopper to permit the bridge pan to move under the delivery mouth of the bucket when the bucket is in delivery position and 80 out of the path of the bucket as it is ascending and descending.

The bucket is mounted on a traveling carriage 10 which travels vertically on the mast, being provided at its lower end with 85 a pair of rollers or wheels 11 bearing on the front face of two of the corner posts of the mast and at its upper end with a pair of rollers or wheels 12 engaging behind the front posts of the mast so that 90 the frame and bucket will be guided in their vertical movement. The bucket it will be noted is on that side of the mast which may be termed the outside, that is, it is on the side of the mast which is normally away 95 from the building or construction work. For raising and lowering the bucket a cable 13 is provided which operates over a suitable head sheave 14 which is carried by the mast cap 15 at the top of the mast. The 100 cable then passes downwardly through the hollow center of the mast and beneath a suitable bottom sheave 16 at the bottom of the mast and thence to the drum of a hoisting engine 17.

The bucket gate is controlled by a lever

18 pivotally mounted on one side of the bucket and having one end connected by a link 19 with the gate. The opposite end of the lever is adapted to engage, when the 5 bucket reaches its delivery position with an adjustable stop 20 secured on the head frame and arranged to project into the path of the lever. This stop 20 is provided with a plurality of bolt openings vertically spaced 10 apart and slightly off the horizontal center of the plate or stop 20. By this arrangement the height of the stop may be varied to vary the opening of the gate, the opening of the gate being at the minimum with 15 the plate at its highest position and at its maximum with the plate lowered to its lowest position. By arranging the openings off center the plate may be turned up side down to get a wider variation in the opening 20 distance of the gate with a minimum sized stop plate. In addition to the stop plate 20 I also provide a tripping arm 21 pivotally mounted so that normally when engaged by the lever 18 it will not operate the lever. 25 However, if at any time it is desired to open the bucket gate to its fullest extent when the bucket is in its raised position, the arm may be drawn downwardly by an operating cable 22 and as the arm is in engagement with the lever 18 with the bucket 30 in its raised position, the gate may be opened to its fullest extent.

The bridge pan 8 is automatically moved to receiving position by an operating arm 35 or lever 23 adapted to project into the path of the bucket and pivotally mounted at its opposite end. This lever is connected by a link rod 24 with the bridge pan so that when the free end of the lever is engaged by the 40 side of the bucket as it ascends to delivery position the bridge pan will be projected beneath the delivery mouth of the bucket.

On the rear or inside face of the mast there is provided a bracket 25 on which is 45 pivotally supported one end of a chute 26. This chute is preferably provided on its under face with a pivot pin socketed in a suitable socket on the bracket so that the chute may be swung on this pivot to various positions. The outer end of the chute is supported by a boom line 27 which extends from the outer end of the chute to a bridle bracket 28 secured at a point on the mast above the bracket 25 and preferably 50 near the top of the mast. As the bucket 5 and chute hopper 4 are mounted on the front of the mast and have a side or transverse delivery and the conveyor is mounted on the rear of the mast with its receiving 55 hopper 29 in proximity to the mast, there is provided for conveying the material from the chute hopper 5 to the delivery chute 26, a conveyor chute 30 the spout of which extends to directly over the hopper 29 and the 60 receiving end which is preferably provided

with a receiving hopper 31, is supported beneath the delivery end of the chute hopper 4. This conveyor chute is preferably supported at its upper or receiving end from the chute hopper by a suitable hanger bolt 70 secured in an angle bracket fastened on one side of the chute hopper 4.

It is obvious that the chute 26 may be extended by adding additional sections as 32 so that the material may be delivered to 75 any point desired.

For conveying additional material for use in construction operations I provide a hoisting platform 33 which travels on the inner face of the mast. Due to the fact that the upper end of the chute 26 is supported at a point considerably higher than the working point on the building there is ample free space below the bracket 25 to permit the hoisting platform to be raised to the highest working point on the building. This hoisting platform is preferably supported from a vertically traveling carriage 34 provided at its lower end with a pair of rollers or wheels 35 bearing on the front face 90 of the two inside angle posts of the mast and at its upper end with a pair of wheels or rollers 36 engaging behind the angles of the inside posts of the mast so that the frame will be guided in its vertical movement. The platform is raised and lowered by means of a cable 37 passing upwardly and over a sheave 38 supported in the mast cap 15 and thence downwardly on the interior of the mast to a bottom sheave 39 and thence to a drum on the hoisting engine 17. It will be noted that by passing the cables controlling the hoisting bucket and hoisting platform down through the hollow mast 100 ample clearance for the operation of these cables is provided without interference with the operation of the concrete chutes and delivery apparatus. Furthermore, due to the placing of the platform on the inside face of the mast it is readily accessible from the building to permit the loading or unloading of the platform and by placing the bucket on the outside face of the mast the mast is not subject to unbalancing strains. Furthermore, in this construction the head 105 frame being mounted on the outside face of the mast and delivery chute being mounted on the inside face of the mast a further balancing effect is obtained.

The mast is capable of being built to various heights and to this end it is made in sections, the various sections being adapted to be connected together by suitable joint plates 40. When the mast has been built up beyond a predetermined point it becomes advisable to provide additional bracing, therefore to this end I provide an intermediate guy arm 41 which is adapted to extend through the mast and be secured thereto and is provided with guy shackles 110 115 120 125 130 135 140

material comprising a mast having an unobstructed passageway through the center thereof, a chute hopper carried by said mast on one side thereof projecting beyond the 5 vertical plane of said side and having its delivery end extending toward and beyond the edge of said side and an elevator bucket carried on said mast on the same side as said chute hopper, the face of said mast between 10 the chute hopper and the base of the mast being free and unobstructed to permit the vertical travel of said elevator bucket on the mast and to the chute hopper, a delivery 15 chute carried on the opposite side of said mast, a transfer chute extending between said chute hopper and delivery chute and arranged exteriorly of the mast, said delivery chute being supported at a point above the

working point on the building with which the apparatus is associated, a material elevator carried on the same side of said mast as the delivery chute, the face of said mast being free and unobstructed between the support for the delivery chute and the delivery chute and the base of the mast to 20 permit vertical travel of the material elevator and cables for operating said bucket and elevator passing upwardly on the face of the mast and downwardly through the center passageway in the mast. 25

In witness whereof, we have hereunto set our hands at Indianapolis, Indiana, this 14 day of January, A. D. one thousand nine hundred and twenty five.

CARL G. SCHMID.

ALVIN C. RASMUSSEN.
